(57) **CLAIM**

The ornamental design for a nail cutter, as shown and described.

DESCRIPTION

FIG. 1 is a perspective view of a nail cutter showing my new design, the broken lines showing the human form being for illustrative purposes only and forming no part of the claimed design;

FIG. 2 is a right side elevational view thereof, the left side view being a mirror image of the right side view;

FIG. 3 is a top plan view of the nail cutter;

FIG. 4 is a bottom plan view thereof;

FIG. 5 is a front elevational view thereof; and,

FIG. 6 is a rear elevational view thereof.
